UNITED STATES PATENT OFFICE

NICHOLAS LALLI, OF PHILADELPHIA, PENNSYLVANIA

SOUND-REPRODUCING AMPLIFIER

Application filed April 22, 1928. Serial No. 103,866.

This invention relates primarily to sound reproducing and amplifying devices, and the principal object of the invention is to provide a speaker of novel form capable of producing sounds in a generally improved manner.

Another object of the invention is to provide a loud speaker which in its novel structural characteristics takes advantage of the superior resonance and acoustic qualities of wood.

Another object of the invention is to provide a loud speaker from which the sounds emanate with substantial uniformity from all sides.

The invention further contemplates the provision of a satisfactory loud speaker at a comparatively low manufacturing cost.

In the attached drawings:

Figure 1 is a vertical section through a speaker made in accordance with my invention;

Fig. 2 is a view in perspective of the detached speaker unit;

Fig. 3 is a front view of the speaker, and

Fig. 4 is a fragmentary diagrammatic section view illustrating a modification.

With reference to the drawings, the speaker comprises a casing 1 which in the present instance is circular in form, as shown in Fig. 3, and which is supported upon a suitable base or pedestal 2. The casing 1 which preferably is made entirely of wood consists of a circular front plate 3 preferably of outwardly dished formation, as shown in Fig. 1, and a corresponding back plate 4 having a central opening 5 in which is mounted the reproducing unit 6.

Extending between the plates 3 and 4 and spacing these plates apart is an annular strip 7 which completes the casing and which as shown in Fig. 1 is preferably provided with a series of openings 8 extending around the entire periphery with the exception of that part to which the base 2 attaches. The casing 1 is reinforced by means in the present instance of a pair of struts 9, 9 which extend between the plates 3 and 4 adjacent the opening 5.

The unit 6 is secured to a circular plate

11 which constitutes a closure for the opening 5 and which may be secured to the back plate 4 by means of screws 22 which pass through apertures 12 in the plate 11 and into the plate 4. As shown in Fig. 2, this back plate preferably is provided with a plurality of openings 13.

The unit 6 may be of any desired type or construction, and in the present instance I have shown the speaking unit housed within a cylindrical casing 14, which latter is secured as stated above to the plate 11. On the opposite side this casing has an opening from which extends in the present instance a small bell-shaped amplifier element 15. The wires 16 by means of which the speaker may be connected to the radio set may attach to the unit 6, as shown, and extend through an aperture 17 in the rear plate 4. In the present instance, I have shown means for adjusting the diaphragm of the reproducing unit after well known manner, this means comprising a knob 18 projecting centrally from the plate 11 to which the unit is attached.

Novel and important features of this construction reside first in the fact that by reason of the attachment of the reproducing unit directly to the rear plate 4 through the plate 11 which is securely fixed to said rear plate and the connection of this plate with the front plate 3 through the struts 9 which are secured to the front plate near the center thereof, the sound vibrations are transmitted to the comparatively large areas of both of these plates, with the result that the sounds are amplified to a marked degree. By solidly securing the diaphragm of the reproducing unit to the side plate of the casing, through the casing 14 in which the diaphragm is mounted, the said side plate functions as a sounding board giving marked resonance to the reproduced tones. It is further found that the amplification covers a comparatively wide tone range. It will further be noted that with this arrangement the sounds emanate from the speaker without any clearly defined directional effect, the sounds emanating in practically all directions with uniform volume.

The design also takes full advantage of the natural resonance and acoustic properties of wood of which the entire casing 1 is made. There is, however, to be no limitation in this respect, since the casing may be made of other materials if this is found desirable. It is further to be noted that the construction is an extremely reasonable one as to the cost of manufacture.

10 It will be understood that there may be considerable modification of the general form of the device without departure from the invention.

15 In Fig. 4, I have illustrated a modification which in all essential respects is similar to the construction illustrated in the other figures, except that in this case the diaphragm of the sound reproducing unit designated by the reference numeral 19 is directly connected 20 with the front plate 3 by means of a rod 21, as clearly illustrated. This gives a direct operative connection between the reproducing unit and the front plate 3.

I claim:

25 1. A sound reproducing amplifier comprising a casing having front and rear plates of wood co-extensive therewith, the front plate being dished outwardly and the rear plate having a central opening, and an annular strip extending between said plates.

30 2. A sound reproducing amplifier comprising a casing having front and rear plates of wood co-extensive therewith, the front plate being dished outwardly and the rear plate 35 having a central opening and a perforated annular strip extending between the said plates.

35 3. A sound reproducing amplifier comprising a casing having front and rear plates of wood co-extensive therewith, the front plate 40 being dished outwardly and the rear plate having a central opening, an annular strip extending between said plates, and reinforcing means between the front and back plates 45 of said casing.

NICHOLAS LALLI.
